[57] ABSTRACT

A portable utility system particularly useful for drastically cooling seawater and/or forming an ice/brine slurry for application to fish. A tube-in-tube evaporator is provided for cooling the seawater while it is drawn into the evaporator by means of a positive displacement brine pump. Seawater is drawn into a tube-in-tube condenser by a coolant pump to remove heat from the system refrigerant and is continuously discharged after it is passed through the condenser coils. A compressor is provided to raise the pressure and temperature of the gaseous refrigerant. A reversible valve enables the flow of refrigerant through the system to be reversed, producing hot water at the output of the evaporator, when desired. The evaporator is formed of a first tube for conveying refrigerant and a second tube positioned in heat exchange relation within the first tube, the second tube conveying seawater to be refrigerated. The condenser may also be formed of a tube within a tube wherein the refrigerant is conveyed in the inner tube and the cooling seawater is conveyed in the outer tube. An in-line dispenser for bacteriostatic agents, or the like, can be provided. The system can supply electrical as well as hydraulic needs and can be used onshore with air cooling in place of water cooling.

PORTABLE UTILITY SYSTEM

FIELD OF THE INVENTION

The field of art to which the invention pertains includes the field of refrigeration systems, particularly with respect to systems providing refrigerated seawater or an ice/brine slurry for direct application to freshly caught fish.

BACKGROUND AND SUMMARY OF THE INVENTION

The principal sources of commercial marketable seafood in the world today are remote in time and distance from their ultimate consumers. Unlike meat products, such as beef, which are actually improved with aging, seafood is highly perishable. Fish begin to deteriorate as soon as caught and immediate refrigeration is the only known way to preserve the original quality of the fish. Much of the world's high quality seafood is taken in warm tropical waters by small craft which typically have no refrigeration system at all or, at best, utilize ice. Therefore, a significant percentage of the fish catch spoils before it can reach processing facilities. It is not uncommon for such spoilage to amount to more than half the value of the catch. Thus preservation and quality control are the fundamental obstacles confronting the advancement of commercial fishing in much of the world today.

The changing technology of fishing actually favors the use of small boats in many areas where new commercial fisheries are being developed. Moreover, there is a growing tendency for large seafood companies to establish canning and processing plants in underdeveloped areas of the world and to buy fish from native fisherman.

Typical fishing boats without refrigeration can keep their catch on the boat for up to a maximum of 24 hours. Thus, fish caught early in the trip may spoil before a full load has been caught. Custom refrigeration systems for such fishing boats have been relatively expensive, often costing more than the market value of the boat itself. The use of the custom refrigeration systems has been limited to shrimp boats of greater than 60 feet in length and this guideline has only been found acceptable in recent years, as the price of shrimp has greatly increased. Thus, inexpensive refrigeration systems could substantially boost the yield for a fishing boat by increasing the amount of marketable fish and, by preserving quality, assuring a higher price per pound of fish at the time of sale.

Prior art devices which utilize chilled seawater are relatively complex and expensive. In addition, these refrigeration systems are not readily repaired by a fishing crew while the boat is at sea. Typical systems which involved the spraying of fish for refrigeration purposes include U.S. Pat. Nos. 2,746,272, 2,982,109 and 3,162,020. Also of interest with respect to the cooling and heating functions of a refrigeration system are U.S. Pat. Nos. 2,887,853, 3,308,877 and 3,453,840. Additional patents which are of background and environmental interest include U.S. Pat. Nos. 1,322,312, 1,192,896, 2,863,037, 2,909,040 and 3,309,891.

In order to overcome the disadvantages of prior art refrigeration systems, the present invention provides an economical, portable source of refrigeration suitable for use in commercial fishing operations by small craft.

In addition, the refrigeration system can also be used on large boats and shore facilities and requires only seawater and ordinary motor fuel for its operation. Refrigeration occurs by the direct contact of the seafood with a stream of refrigerated seawater or an ice/brine slurry. An advantage of the system is that immediate chilling of the fish occurs, which is superior to ice or other conventional refrigeration methods. When utilized with fish caught from warm ocean water, the refrigerated seawater is lowered to about 31°-39°F, thereby reducing spoilage from enzymatic attack and suppressing the activity of mesophilic bacteria of these waters which are substantially dormant at temperatures below 50°F. In addition, cold water fish may spoil from psychrophilic bacterial attack at temperatures as low as 19°F. Thus, for application with cold water fishing vessels the system is designed to produce ice/brine slurries, without additional salt requirement, from recycled refrigerated seawater at temperatures as low as 15°F. The system thus has the capability of freezing as well as chilling the fish.

The refrigeration system is designed to produce an ice/brine slurry by taking advantage of the fact that seawater has no definite freezing point. Due to its dissolved minerals, the seawater does not solidify at once, but forms ice (fresh water) crystals suspended in the residual brine as its temperature is reduced, the first crystals being formed at about 29°F. With further reduction of temperature, more and more crystals form, taking water out of the solution and leaving a brine of higher and higher salt content as the matrix. The slurry of ice crystals and brine becomes more and more viscous with decreasing temperatures.

In the specific embodiment illustrated, a refrigeration system is provided to convert seawater into refrigerated seawater or an ice/brine slurry for direct application to freshly caught fish. A pump is provided for drawing seawater into an evaporator of the refrigeration system. The pump is of a positive displacement configuration so that ice crystals are pushed through a tube by increasing pressure as the ice/brine slurry becomes more viscous. The evaporator of the system is formed of a first tube for conveying a refrigerant and a second tube member positioned within the first tube member through which the seawater is pumped. In addition, a pump is provided for continuously discharging water through a condenser so as to remove heat from the compressed refrigerant. The condenser is also constructed tube-in-tube. Cooling seawater passes through the inner tube. Heat is removed from the condenser by seawater in the outer tube.

In a further embodiment, a reversible valve is provided for reversing the flow of refrigerant through the system, thereby producing hot water at the output of the evaporator.

As a result of providing the novel portable refrigeration capability, as outlined above, small boats will be able to remain in the fishery for much longer periods of time. As a consequence, greater need will exist for supportive utilities such as electrical power, hot cleaning water, drinking water, bilge pumping and other water transport capability. The system described herein also provides these utilities. Thus, the engine constituting the pump motor can be used to provide electrical power with appropriate takeoffs. The ice slurry capability can be used to provide drinking water by the freezing method of desalination. Hot water can be pro-

vided as noted above. Accordingly, a complete utility system is provided. The system can be used on-shore by simply replacing the water cooling components with well known air cooled components.

The advantages of this invention, both as to its construction and mode of operation, will be readily appreciated as the same becomes better understood by reference to the following detailed description when considered in connection with the accompanying drawing in which like referenced numerals designate like parts throughout the figures.

BRIEF DESCRIPTION OF THE DRAWINGS

FIG. 1 is a schematic illustration of a refrigeration system made in accordance with the present invention; and

FIG. 2 is a detailed view, partly in section, of the evaporator utilized in the refrigeration system of FIG. 1.

DETAILED DESCRIPTION

Referring to FIG. 1, there is shown an exemplary embodiment of the refrigeration system made in accordance with principles of the invention. The refrigeration system comprises a motor 12 which normally may be air-cooled and can be conveniently mounted on a deck of a small boat. The motor 12 can be a fossil, and fuel internal combustion engine, such as spark ignition or diesel can be electrically or hydraulically driven or driven by a belt driving mechanism. The motor 12 is used to drive a shaft 14 having a pulley 16 thereon. The shaft 14 in addition is connected through a clutch member 18 to a compressor 22 and is used to drive the compressor 22. The compressor 22 comprises a suction input section 24 and discharge output section 26. The pulley 16 has a belt 28 thereon which is used to drive a second pulley 32. The pulley 32 is mounted on a shaft 34 which is used to drive a brine pump 36 and also is connected through a coupling 38 to a coolant pump 42. Alternatively the brine and coolant pumps 36 and 42 can be tandemly disposed on the same shaft and/or driven off the same belt as the compressor. The refrigeration system is normally utilized to chill seawater or if desired, to recycle the chilled seawater, reducing the temperature of the seawater sufficiently that a slurry is produced.

Seawater is positively drawn into the refrigeration system by means of the brine pump 36 through a strainer 44. Normally, the suction prime of the seawater to the pumps is maintained by a check valve 45 once operation is established in order to avoid dry sucking by the pumps. The strainer 44 prevents gross entrained solids in the seawater from entering the system. The seawater is pumped through a tube 46 by the brine pump 36 into the evaporator 48 of the refrigeration system. The chilled seawater emerges from the evaporator 48 through a hose outlet 52 where it can be used as desired. Thus, (not shown) the outlet 52 can be connected, to a treating tank which, in turn, is connected through a valve to the inlet of the brine pump strainer. Other means of distributing the flow can be used such as high velocity spray, fog, and the like.

Liquid refrigerant, which may be any conventional refrigerant such as any common halogenated hydrocarbon refrigerant, e.g., Freon, leaves a capillary expansion tube 64 and enters the evaporator 48 through a line 54 where it boils at a low temperature to produce

cooling and emerges therefrom into an output refrigerant line 56. The refrigerant is then conveyed through a reversing valve 58 into a line 60 and then to an accumulator vessel 62 as shown by the arrows. At the accumulator 62, heat from the liquid refrigerant flowing in the capillary tube 64 contacts the accumulator 62 at a point upstream from the line 54, flows through the vessel wall and into the refrigerant vapor leaving the evaporator 48. Such heat transfer causes the vaporization of any remaining refrigerant liquid trapped in the accumulator providing protection to the compressor 22 from liquid entrainment. The heat transfer also provides a high degree of thermal efficiency by recovering unused refrigeration effect from the unevaporated refrigerant leaving the evaporator (recuperation).

The refrigerant vapor in the accumulator 62 is then conveyed by line 66 to the suction end 24 of the compressor 22 where the pressure and temperature of the gaseous refrigerant is raised. The refrigerant is discharged from the discharge end 26 of the compressor to the reversing valve 58 and then passes through a line 72 and then through a condenser 74. To expedite removal of heat from the refrigerant at the condenser stage, seawater is carried through a strainer 76 by means of the coolant pump 42 and passes from the coolant pump through a line 78 through the condenser 74. The cooling water is emitted from the condenser through a line 80 and is then discharged overboard.

The strainer 76 and check valve 82 are similar to the strainer 44 and check valve 45 and functions with the coolant pump 42 in a manner identical to that described with respect to the brine pump 36. The functions of the brine pump and the coolant pump can be combined with appropriate valving so as to provide sufficient seawater for both cooling the condenser and providing input seawater to the evaporator.

The output liquid refrigerant from the condenser is conveyed through a strainer-dryer 84 and is then conveyed through the capillary tube 64. The refrigerant in the capillary tube 64 is then conveyed to a second strainer-dryer 86 which provides the same function as the strainer-dryer 84 during reverse operation as will be explained hereinafter. The output of the strainer-dryer 86 is then connected to the refrigerant line 54 at the input of the evaporator 48. Thus, the refrigerant cycle is completed and the desired chilled seawater is produced at line 52.

Should it be desired to produce hot water at the output line 52, it is merely necessary to reverse the connections of the valve 58 so as to reverse the flow of the refrigerant through the system as shown by the dotted lines 88 and 90 in the valve 58. In the hot water mode of operation, refrigerant from the discharge end 26 of the compressor 22 is conducted through the line 88 and the line 56 and into the evaporator 48 whereupon the resultant heat exchange therein produces hot water at the output of the line 52. The refrigerant passing through the evaporator in the line 56 exits through the line 54 where it enters the strainer-dryer 86 which, as previously mentioned for reverse operation, will produce the same function as the strainer-dryer 84. The refrigerant then passes through the capillary expansion tube 64, the strainer-dryer 84, condenser 74, line 72, line 90 of valve 58, line 60, the suction accumulator 62 and then enters the suction end 24 of the compressor 22. Thus, the system can be used to produce hot water rather than chilled water, when such is desired.

It may be desired to operate the fishing vessel in waters where the storage temperature of cold water fish must be reduced to a degree greater than provided by the refrigerated chilled water at the output of the evaporator 48. An ice/brine slurry can be provided by recycling the chilled water at the output 52. This can be accomplished by reconveying the chilled seawater through the brine pump 36 as shown by dashed line 92. This provides the capability of adjusting the output temperature while preserving the monotube positive displacement character of the system. Thus, the resultant recycling can reduce the temperature of the slurry at the output of the hose 52° to 15°F. Thus, the capability of continuously freezing seawater is provided. Since the brine pump 36 is a positive displacement pump, any ice crystals formed in the single line 46 or in the monotube section of the evaporator connected to the line 46 are pushed therethrough by the increasing pressure applied by the pump as the seawater becomes more viscous or as the tube becomes restricted. The monotube evaporator design coupled with the positive displacement brine pump creates an increasing shearing action at any spot where local build-up of ice scale would occur, thereby keeping the tube free-flowing, the ice/brine slurry well mixed and the ice crystals extremely fine in texture.

Referring now to FIG. 2, there is shown a preferred embodiment of the evaporator 48 utilized in the construction of the refrigeration system of FIG. 1. The evaporator 48 comprises an inner coiled tube 102, one end of which is connected to the output line 52. Surrounding the coiled line 102 in an outer coiled line 104, one end of which is connected to the refrigerant line 54 and the other end of which is connected to the refrigerant line 56. In a typical construction, the line 102 is formed of a $\frac{3}{8}$ inch outer diameter tube of about 50 feet in length, and the tube 104 surrounding the tube 102 is formed with a $\frac{3}{4}$ inch outer diameter. Such a coiled tube-within-a-tube construction efficiently produces chilled seawater having a temperature in the range of 29°-39°F, and an ice/slurry when recycled as above.

The condenser 74 may be constructed in a manner similar to the evaporator 48 wherein an inner tube containing the seawater is surrounded by an outer tube containing the refrigerant which is cooled and condensed as it passes in annular countercurrent flow arrangement with the seawater in the inner tube. Coiling of the tubes as illustrated results in an advantageous economy of space and portability. The evaporator and condenser coils can be nested one within the other, permitting compact enclosure which facilitates sliding, skidding and other handling and installation of the unit. The enclosure can be made as a water-proof hull for flotation on the surf and between boats at sea.

Referring back to FIG. 1, there is illustrated, in shadow, a further embodiment wherein means are provided to chemically treat the brine applied to the fish.

Specifically, a hold tank 55 is provided which may be in the form of a container, pressure vessel, flexible feed bag, drum or the like, and which is connected into the brine pump strainer 44 through a valve 59 as shown or by immersion of the strainer 44 therein. The hold tank 55 is filled with a treating agent for the fish which may be a bacteriostatic material. For example, liquid bacteriostats may be thus provided, or a source of carbon dioxide can constitute the holding tank 55. In each case, there is provided a metering capability not presently available.

I claim:

1. A portable single drive, positive displacement utility system for converting seawater into refrigerated seawater, comprising:

single drive means;

an evaporator for lowering the temperature of seawater, said evaporator comprising an outer coiled evaporator tube and an inner coiled evaporator tube within and coextensive with said outer evaporator tube and having a discharge end extending therefrom;

a refrigerant condenser comprising an outer coiled condenser tube and an inner coiled condenser tube within and coextensive with said outer condenser tube and having a discharge end extending therefrom;

refrigerant tube means for connecting said outer evaporator and condenser tubes constituting with said outer tubes a refrigerant line;

strainer means in said refrigerant line;

compressor means connected to said refrigerant line for circulating refrigerant therethrough and driven by said single drive means;

means for pumping seawater through said inner evaporator and condenser tubes comprising at least one positive displacement pump, and strainer means therefor, connected to said inner evaporator and condenser tubes and driven by said single drive means, whereby to provide cooled seawater discharge from said inner evaporator tube discharge end and heated seawater discharge from said inner condenser tube discharge end;

valve means for reversing the flow of refrigerant through said refrigerant line whereby to produce hot water at the discharge end of said inner evaporator tube.

2. A system in accordance with claim 1 wherein said condenser and evaporator coils are nested.

3. A system in accordance with claim 1 and further comprising means for recirculating said refrigerated seawater at the output of said refrigerator through said pump means to form the output of said inner evaporator tube as an ice/brine slurry.

4. A system in accordance with claim 1 and further comprising means for applying fish treating agents to said pump upstream of said evaporator.
